WINDOW

George Arthur Wiggins and George Beresford
Martin, Hamilton, Ontario, Canada

Application July 2, 1936, Serial No. 88,541

1 Claim. (Cl. 20—40)

This invention relates to mountings and means for operating revoluble windows and window screens.

One important object of the invention is to provide mounting and means for revolving a pair of coaxially arranged discs, one of which is partially glazed and partially open, and the other being partially screened and partially open independently and selectively in either direction and for locking them in annularly selective positions.

Another important object is to provide mechanism of this character which will be simple, efficient, and inexpensive to produce.

With the above and other objects in view as will be hereinafter apparent, the invention consists in general of certain novel details of construction and combinations or parts hereinafter fully described, illustrated in the accompanying drawing and specifically claimed.

In the accompanying drawing like characters of reference indicate like parts in the several views, and:

Figure 1 is an inside view of a window as constructed in accordance with this invention.

Figure 2 is a vertical cross-section taken on the line 2—2 of Figure 1.

Figure 3 is a partially broken detailed inside face view of the semi-glazed ring.

Figure 4 is a vertical cross-section of the same taken on the line 4—4 of Figure 3.

Figure 5 is a partially broken detailed inside face view of the semi-screened ring.

Figure 6 is a vertical cross-section of the same taken on line 6—6 of Figure 5.

Figure 7 is an enlarged detailed top view of the window operating device.

Figure 8 is a partial median cross-section of the window operating device.

Although it is to be understood that the invention is applicable to all forms of vehicle windows, it is here shown in connection with a motor vehicle door window.

Motor vehicle doors and bodies beneath the windows are hollow and contain the window panes when they are dropped or lowered from their closed position, and similarly the doors or bodies beneath the windows in the present invention are hollow.

In the embodiment of the invention herein illustrated, the frame of the door is indicated by the numeral 10, and 11 and 12 indicate the inner and outer walls, respectively. The top portion of each wall is provided with a substantially semi-circular opening 13, which open-

ings register so that visibility is obtained through both. Secured in the upper part of the frame 10 is a substantially semi-circular channel. Concentric to this channel 14 and on the wall 12 is a boss 15, and similarly on the wall 11 is a boss 16. The portion of the walls 11 and 12 between the channel 14 of the frame 10 form spandrels 11' which are preferably glazed although they are not necessarily so.

On the outside of the wall 11 and concentric with the boss 16 there is rigidly mounted a bearing 16¹ which carries at its inner end a flange 17 permanently fixed to the wall 11. The boss 16 is tubular in construction and through this boss passes a diametrically increased portion 17¹ of a tubular revolvable member 17² journalled in the bearing 16¹, and through which passes a shaft 18. The shaft 18 is provided with a polygonal portion 19, whereon is fitted a disc 20 having a glazed portion 21 and an open portion 22. The glazing of this disc may be accomplished in any approved manner, and the disc is here shown in two sections between which the glass is clamped. The shaft 18, as well as being journalled at one portion of its length in the member 17², is journalled at its outer end in a conforming recess 15¹ in the boss 15, and this recess is of sufficient depth to permit the said shaft to be partially withdrawn and still provide bearing surface therefor. The shaft 18 also has an operating handle or knob 23 on its outer end, which is reduced in diameter as indicated at 18¹, and this shaft is pressed inwardly by a helical expansion spring 24 inserted between the shoulder 18² of the shaft and a bushing 18³ in which the said reduced portion of the shaft is journalled and against which the hub 23¹ of the knob 23 abuts. It will thus be seen that the handle 23 is forced inwardly by the spring 24. This shaft 18 has the disc 20 mounted thereon, the said disc being provided with a concentric polygonal opening 25 which fits on the conformingly polygonal shaft portion 19. This polygonal portion 19 extends inwardly past the disc 20 and into a conforming enlargement 15² of the recess 15¹, and thus it will be seen that the disc 20 can not be rotated so long as the portion 19 of the shaft engages the said conforming enlargement 15², but on moving the shaft portion 19 clear of the inner face of the boss 15 the disc 20 may be freely rotated. Furthermore, it will be observed that there being as many possible annular positions of the disc 20 as there are sides of the shaft portion 19 the disc 20 may be selectively locked in any of these positions on the release of the handle 23, whereupon the shaft 18 will

move inwardly under the influence of the spring 24 and the shaft portion 19 re-engage the conforming enlargement 15².

The bearing 16¹ is provided with spaced openings 26 arranged diametrically opposite each other so that a plunger 27 slidably supported in a bracket 28, which is mounted on an arm 28¹ on the tubular member 17², and pressed inwardly by a helical expansion spring 29 may engage in said openings when the tubular member 17² is turned by means of the arm 28¹ to one position or another. A knob 30 provided with a stem 31 is slidably mounted in the arm 28¹, a slot 32 being provided in said arm so that the stem 31 may slide up and down and thus release the plunger 27 from the opening wherewith it is engaged. It may be noted that the knob 30 is used both to disengage the plunger 27 and to turn the tubular member 17² alternately from one side to the other.

20 The member 17² is freely revolvable in the bearing 16¹ and the inner end of this member is provided with a key 33 which is adapted to fit permanently in a conforming slot 34, through which the shaft 18 also freely passes, formed in a second disc 35 which also fits in the channel 14 close to the glazed disc, and one half of which is freely open while the other half is provided with wire screen 36.

In the operation of the disc 35, the plunger 27 serves to locate this member in either of its two positions. When located in one position the screen closes the opening 13 and when in its other position the screen leaves the opening free.

In Figure 1 the glazed portion of the disc 20 is shown in the position to close the opening 13 while the screen portion of the disc 35 is shown in its position when the opening 13 is unscreened. That is to say the opening 13 is closed by the glass but not by the screen, although it is understood that the opening 13 may be closed by the glass and by the screen at the same time. In Figure 3 the disc 20 is shown with the glass portion in the position to close the opening 13, and in Figure 5 the disc 35 is shown with the screen portion in the position to close the opening 13.

45 There has thus been provided a simple and ef-

ficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

We claim:

In a mechanism of the class described, a bearing, a tubular member journaled in the bearing, a key on a projecting end of said member and having a shoulder abutting the bearing, a radial flange on the opposite end of said member and abutting the bearing, an arm on said flange, a bushing in the flanged end of said member, a sliding and revolving shaft partially journaled in said member and provided with a polygonal portion and with a reduced portion creating a shoulder, the reduced portion of said shaft being journaled in the bushing, a helical spring around said reduced portion and expanding against the shoulder of said shaft and against the bushing, means on the end of the reduced portion of the shaft for jointly turning the shaft in either direction and for drawing it outwardly, said means being urged inwardly against the bushing by means of said spring, a disc keyed onto the key, a second disc loosely keyed onto the polygonal portion of the shaft, a boss having a recess, the deeper portion of the recess being conformingly round to receive the end of the main portion of the shaft and a shallow portion thereof being conformingly polygonal to receive a portion of the polygonal portion of the shaft in annularly selective positions, a plunger slidably associated with the arm and selectively engageable with a plurality of spaced recesses in the periphery of the bearing, spring means urging said plunger into said recesses, and means for jointly effecting contramovement of the plunger and for revolving the tubular member.
